DENTAL MATRIX

Ivar E. Sjveland, St. Paul, Minn.

Application March 25, 1935, Serial No. 12,873

4 Claims.

(Cl. 32—63)

This invention relates to the method of making cervical and other inlay and plastic fillings for teeth, and the means of obtaining virtually a perfect wax impression or pattern for the inlay, in a simple manner, thus carrying out a finer dental technique.

In making cervical and other inlays or fillings heretofore, it has been difficult to obtain the wax impression of the cavity owing to the fact that the wax impression or pattern could not be readily removed without possible distortion or injury. Heretofore, the impression wax was placed in the cavity in the tooth and then a heated sprue inserted in the wax. With this old method, the sprue was held in place until the wax had set about the sprue and then the wax impression was removed on the end of the sprue. It will be apparent that unless the dentist was extremely careful in this old method, he might injure the form or shape of the wax impression or pattern in inserting the sprue and trying to remove it from the cavity. This I have entirely overcome with my method by providing waxed sprues of the desired character for different cavities, and apparatus for inserting the waxed sprue into the cavity so as to obtain a virtually perfect wax impression.

A feature of my method resides in providing waxed sprues of different shapes and characters so that they may be readily adapted to different cavities. These waxed sprues are in the form of a short wire having the impression wax formed in the desired shape on one end thereof. In one form, the impression wax on the sprue may be conical so that the apex thereof may assist in guiding the wax into the cavity. In another form, the wax may be cylindrical on one end of the sprue wire, or of such other shape as may be desired. These short wire sprues with the waxed ends are supplied to the dentist in the quantity and shape desired.

The invention includes a suitable matrix plate having a tubular supporting portion through which the outer end of the sprue may extend.

In carrying out my method, I provide a suitable forming tool for forming the matrix plates to the outer contour of the tooth to be filled. I also provide an applying tool for holding or supporting the matrix plate with the sprue pin extending through the same and the waxed end of the sprue adjacent to the matrix plate. This applying tool holds the matrix plate and sprue in applying position and is provided with a spring urged socket into which the end of the sprue pin fits. The applying tool permits the

waxed sprue to be pressed by the matrix plate into the cavity, the matrix plate fitting closely to the outer contour of the tooth and pressing the impression wax into the cavity firmly, so as to obtain a true impression of the cavity while the impression wax is soft enough to be pressed into the same. The spring urged socket which engages the end of the sprue pin ejects the sprue as the applying tool is drawn away from the tooth and the sprue pin remains projecting from the impression which has become set in the cavity in the tooth. Then when the impression wax is sufficiently set with the sprue pin anchored therein and projecting therefrom, the mold may be removed from the cavity by engaging the sprue pin. By this method I obtain a virtually perfect impression of the cavity in the tooth because the sprue pin does not have to be inserted after the impression is formed, but rather the wax impression or pattern is formed with the sprue pin embedded therein while the applying tool holds the same in position until the impression wax has thoroughly set.

My method provides a better dental technique in the making of surface fillings on the outer faces of teeth, such as cervical and other inlays and plastic fillings. The applying tool with the matrix plate may be used to apply the plastic fillings in a more efficient manner than has been accomplished heretofore.

The features of my method of making cervical and other inlay and plastic fillings will be more fully apparent from the disclosure of the tools desirable in carrying out the same and the manner in which the waxed sprues are handled and applied to obtain the desired impression of the cavity.

The drawing is for the purpose of illustrating the carrying out of my method and showing the apparatus, such as the tools desirable, and the construction of the waxed sprues and matrix plate as used in one form in carrying out my method.

In the drawing, Figure 1 is a side elevation of a set of upper and lower teeth in biting position, showing a cavity which is about to be filled by my method.

Figure 2 is a perspective view of the matrix plate used in carrying out my method.

Figure 3 illustrates the bending and shaping pliers used for holding and forming the matrix plate to the shape of the tooth.

Figure 4 illustrates a matrix plate bent into the desired shape.

Figure 5 illustrates a waxed sprue of one form.

Figure 6 illustrates a waxed sprue of another form.

Figure 7 illustrates a waxed sprue of still another form.

5 Figure 8 illustrates the applying tool with a waxed sprue and matrix plate held as a unit and ready for taking an impression of a cavity in a tooth.

10 Figure 9 is a sectional detail of the operating end of the applying tool, showing its position in taking an impression of a cavity in a tooth and showing the manner in which the matrix plate operates to press the impression wax into the cavity and showing the position of the sprue pin 15 in the applying tool cushioned by the spring means in the tool.

15 Figure 10 is a section of a tooth, which shows the impression wax with the sprue pin projecting therefrom after the impression of the cavity has 20 been taken and the applying tool with the matrix plate has been withdrawn from the tooth.

25 Figure 11 illustrates a perspective of the removed sprue pin and impression after the wax impression of the cavity has been taken by my method, as illustrated in Figures 9 and 10.

Figure 12 is an enlarged section of a waxed sprue.

30 In carrying out my method of making cervical and fillings of a similar character, I use a matrix plate 10 which is formed of thin sheet metal or other suitable material, such as celluloid. This matrix plate 10 is provided with a tubular shank 11 having a hole 12 extending through the same.

35 The matrix plate 10 is adapted to be cut with the desired peripheral shape and may be formed by supporting the same in the holding pliers with the shank 11 extending in the slot 13 of the bifurcated end of the pliers A as illustrated in Figure 3. One of the jaws 14 of the pliers A 40 may be round in cross-section so that the matrix plate 10 may be formed around the same while it is held between the jaws of the pliers A.

45 To assist me in further carrying out my method I employ waxed sprues B, illustrated in Figures 5, 6 and 7. The sprues B consist of a wire shank 15 on one end of which a body of wax 16 is formed in any desired shape. Thus I provide a waxed sprue B with a wire shank 15 and with a body of wax such as 16 in spherical form, 16' in 50 conical form, or such as in the form illustrated by 16'', or in any other shape that may be desired. These sprues B may be furnished to the dentist in any quantity and shape that he desires.

55 The advantage to the dentist in having waxed sprues B with the impression wax on the end of the same will be apparent in that the dentist may take a sprue of the desired shape and size for the respective cavity and secure an impression of the cavity to be filled very readily.

60 Further, my method is carried out by the use of the applying tool C which is formed with a handle portion 17 from which projects the operating arm 18. On the working end of the operating arm 18 I provide a cylinder 19 in which is 65 located a coil spring 20 which is adapted to resiliently position the socket 21 within the cylinder 19 so as to normally urge the socket 21 toward the tubular collar 22 which is positioned in the outer end of the cylinder 19. The collar 22 is 70 formed with an axial opening 23 which is adapted to receive the shank 11 and the sprue B collectively, as illustrated in Figures 8 and 9.

75 In carrying out my method of making cervical and other fillings in the operation of securing the impression of the cavity in the tooth, the

matrix plate 10 is formed into the desired shape by first trimming the edge of the plate 10 to the shape desired and then forming the same while held by the pliers A. Then the desired sprue B is placed with its shank 15 extending into the shank 11 of the matrix 10 and then this unit consisting of the matrix and sprue, is placed into the sleeve-like collar 22 of the applying tool C. Then the dentist is ready to take an impression of the cavity 24 and this is done by having the impression wax 16 warm enough to readily form itself to the shape of the cavity and then by taking the applying tool C and pressing the matrix plate 10 against the outer surface of the tooth D forcing the impression wax into the cavity 24 firmly, 15 and as soon as the same has set, the applying tool is withdrawn, whereupon the impression wax 16 will remain in the cavity 24 and the pin 15 of the sprue B will project from the same as illustrated in Figure 10. The dentist may then remove the sprue B with the wax impression E of the cavity 24 formed thereon as illustrated in Figure 11. It will therefore be apparent that with my method of securing the impression of a cavity to be filled, a dentist may accomplish the same with a finer technique than was possible heretofore and with full assurance of obtaining virtually a perfect wax impression of the cavity in the tooth such as D. Heretofore, the dentist could not carry out this fine dental technique, not being advised of my method or manner of carrying out the same, and not having the waxed sprues, matrix plate or applying tool it was not possible for the dentist to easily obtain a virtually perfect impression of the cavity to be 30 filled. With my method, cervical and other fillings may be made very readily by the dentist with full assurance of obtaining a perfect impression of the cavity, and the wax impression is easy to handle owing to the fact that the sprue 40 wire 15 is firmly embedded in the central portion of the impression.

The wire shank 15 of the sprue B may be threaded or formed with a roughened end at 15' so as to more firmly hold the wire shank 15 embedded in the wax 16'. Therefore, my method of making cervical and other fillings comprises preparing a matrix plate to the desired shape, connecting a waxed sprue with the matrix plate so that they may be operated as a unit, then supporting this unit of matrix plate and sprue in a manner to permit the impression wax to take a true impression of a cavity to be filled. When the impression is taken, the sprue wire permits the easy removal of the wax impression of the cavity without distorting or injuring the impression and then the dentist may cast a true inlay. Further, the method provides a means of making plastic fillings by using the matrix plate to support the plastic filling and then with the applying tool forcing the plastic filling into the cavity. Thus I provide a method wherein the finest dental technique may be accomplished in making fillings of the character set forth, with the greatest 55 of ease.

I claim:

1. A matrix for filling dental cavities including a flexible plate formed to the curvature of the tooth, and a hollow shank secured thereto 70 providing an opening entirely through the shank and plate.

2. A matrix for supporting wax including a plate of soft material flexible to fit the curvature of a tooth, and a shank projecting from one 75

surface thereto having an opening extending through said shank and plate.

3. A cavity filling means comprising a matrix plate to fit the outer conformity of a tooth, said plate having an opening therein, and means supporting cavity filling material adjacent said plate including a sprue extending through said opening having cavity filling material on the end thereof.

4. A cavity filling means comprising a matrix plate to fit the outer conformity of a tooth, a shank thereupon, said shank having an opening therethrough extending also through said plate, and means for supporting impression material adjacent said plate including a sprue bearing impression material extending through said opening. 5
